UNITED STATES PATENT OFFICE

171,025

COMBINATION POCKET TOOL

Ion Bochory, New York, N. Y.

Application February 29, 1952, Serial No. 18,734

Term of patent 14 years

(Cl. D54—13)

To all whom it may concern:

Be it known that I, Ion Bochory, a displaced person, formerly a citizen of Rumania, and a resident of New York, in the county of New York and State of New York, have invented a new, original, and ornamental Design for a Combination Pocket Tool, of which the following is a specification, reference being had to the accompanying drawing, forming a part thereof.

Figure 1 is a front elevational view of a combination pocket tool, showing my new design and illustrating the hinged sections swung into an angular relation to each other;

I claim:

The ornamental design for a combination pocket tool, as shown.

ION BOCHORY.
